UNITED STATES PATENT OFFICE

ALBERT LINDSAY DOERING, OF GERMANTOWN, PENNSYLVANIA, ASSIGNOR TO J. S. THORN COMPANY, OF PHILADELPHIA COUNTY, PENNSYLVANIA, A CORPORATION OF PENNSYLVANIA

METALLIC WINDOW STRUCTURE

Application filed December 30, 1929. Serial No. 417,380.

My invention is applicable to what are known as double hung windows, including a jamb frame in which two sash frames are mounted to reciprocate parallel with each other, and relates particularly to means for maintaining the sash frames in weather-tight relation with the jamb frame without interfering with the freedom for reciprocation of said sash frames. Such means include flanges 5 projecting from the sash frames parallel with the plane of the latter and fitted in corresponding grooves in the jamb frame, and a removable weathering strip detachably connected with the jamb frame between the sash 10 slideways in the jamb frame. Said sash flanges are provided with means for detachable connection with chains or other flexible connectors from the sash frames to sash counterbalance weights and, as hereinafter 15 described, the construction and arrangement are such that removal of a section of said weathering strip affords access to the connections between the sash frames and the counterbalancing means, which means are 20 concealed when the weathering strips are in their normal position in the jamb frame.

My invention includes the various novel features of construction and arrangement hereinafter more definitely specified.

25 In the drawings, Fig. I is a front elevation of a typical embodiment of my invention in a double hung window structure.

Fig. II is a fragmentary vertical sectional view of the structure shown in Fig. I, taken 30 on the line II, II, in Fig. I, with adjoining portions of the building structure.

Fig. III is a plan sectional view of one side of the jamb frame, taken on the line III, III, in Fig. I.

40 Fig. IV is a fragmentary sectional view taken on the line IV, IV, in Fig. I.

Fig. V is a fragmentary sectional view taken on the line V, V, in Fig. I.

Fig. VI is a fragmentary sectional view 45 taken on the line VI, VI, in Fig. I.

Fig. VII is a fragmentary elevation of the left hand side of the lower sash style shown in Fig. III.

50 Referring to Fig. I; said window structure includes the window frame comprising a lin-

tel 1, opposite jambs 2 and 3, and a sill 4 which are connected in rigid relation. The upper sash 6 and lower sash 7 are mounted to reciprocate in said window frame and are respectively counterbalanced by weights 8 and 9. 55

Referring to Fig. II, said lintel 1 is conveniently formed of two pieces of sheet metal 11 and 12 which have their edges interlocked, as indicated at 13. Said lintel piece 11 is pressed to form the finish molding 15 upon 60 the outer face of the frame, and the finish molding 16 upon the inner face thereof, and is pressed to form the two grooves 17 and 18 adapted to receive flanges 19 and 20 projecting upwardly from the top rail 22 of the 65 upper sash 6.

Said top rail 22 of the upper sash 6 is conveniently formed of two pieces of sheet metal 23 and 24; said flanges 19 and 20 being in 70 unitary relation with said piece 23 and being 75 of inverted J-shape to receive the flange 25 on said rail piece 24. Said top rail piece 23 also has the downwardly extending flange 27 forming a recess for the glass 28 which is seated in putty 29 or other suitable cement. 75

Said upper sash 6 has the bottom or meeting rail 31, conveniently formed of a single piece of sheet metal bent upon itself at its opposite edges to form the drip flange 32 at the outer edge of said sash and the weather- 80 flange 33 at the inner edge of said sash. Said rail 31 is also bent intermediate of its edges to form the shoulder 35 to support the glass 28, and to form the channel 36 adjoining said weathering flange 33 to hold the 85 packing 37 which may be a piece of asbestos fabric, adapted to seal the joint between said bottom rail 31 of the upper sash and the top rail 39 of said lower sash 7.

Said top rail 39 is conveniently formed of 90 two pieces of sheet metal 40 and 41. Said piece 40 is bent upon itself at its outer edge to form the weathering flange 43 adapted to fit in airtight relation with the packing 37 in the channel 36 of the bottom rail 31 of the upper sash 6, when the meeting rails of said sashes 6 and 7 are in the closed position shown in Fig. II. The opposite, and inner, edge of said top rail piece 39 is bent to form a finished bead 45 which interlocks with said 11

piece 41, as shown. Said top rail piece 39 is bent intermediate of its edges to form the channel 47 to hold the edge of the glass 48 which is seated in putty or other suitable cement 49 in said recess. Said top rail piece 41 has flanges 51 and 52 at its respectively opposite edges, closely fitting in the recess 53 in said rail member 39. The block 55 in said recess 53 has screw sockets 56 for reception of sash fastening means, and reinforces said top rail 39 of the lower sash 7 intermediate of its width.

The bottom rail 57 of said lower sash 7 is also conveniently formed of pressed sheet metal, including the outer piece 58 which is bent intermediate of its edges to form the flange 59 to retain said glass 48. The opposite edges of said bottom rail piece 58 are inwardly turned to form the J-shaped flanges 60 and 61 which are of different extent, as shown, to fit the slope of said sill 4. Said flanges 60 and 61 receive the flanges 62 and 63 on the other bottom rail piece 65. Said piece 65 is bent to form the hollow flange 66 engaging the flange 67 of the flexible resilient weathering strip 68 which is adapted to yieldingly bear upon the sill 4, and thus make a weather-tight joint between said sill and the sash 7.

As shown in Fig. II, said sill 4 is conveniently formed of a single piece of sheet metal having its opposite edges inwardly turned at 70 and 71 to reinforce it and incidentally engage cementitious material 72 on the building wall 73 which supports the window structure aforesaid.

Referring to Figs. III, IV, and V, it is to be understood that each of the jamb frames 2 and 3 is formed of two pieces of sheet metal 76 and 77, which are detachably connected as hereinafter described. Said piece 76 has its opposite edges 78 and 79 bent to J-shaped and is pressed intermediate of its edges to form the outer finish molding 81 and the inner finish molding 82. The other jamb piece 77 has its opposite edges 84 and 85 respectively fitted in said J-flanges 78 and 79 of the piece 76, and is bent intermediate of its width to form vertically extending grooves 86, 87, 88, and 89, and is normally held in rigid relation with the jamb piece 76 in the position shown, by vertical series of screws 91 which extend between said grooves 87 and 88 and are in threaded engagement with respective yoke bars 92 which have inwardly turned ends 93 and 94 respectively overlapping said J flanges 78 and 79, as shown. Each of said jamb members 2 and 3 is also provided with removable weather strip sections 96 which are detachably held in rigid relation with said jamb frame plate 77 by screws 97. Each of said weathering strips 96 is channel shaped, having opposite parallel flanges 98 and 99 extending into said grooves 87 and 88,

and each preferably with a spring weathering cap 100, formed of sheet bronze.

Said jamb grooves 86 and 87 are respectively adapted to receive, in weathering relation, the flanges 101 and 102 of the opposite side styles of the upper sash 6. Each such member is conveniently formed of a single piece of sheet metal 103, and said flange 101 is reinforced at its edge by bending said sheet metal 103 back upon itself, as indicated at 105. I also prefer to provide each such reinforced portion of said sash flanges with a spring weathering cap 106, preferably formed of sheet bronze, and as indicated in Fig. III. Said flange 102 is J-shaped at its edge to embrace in its bight the flange 98 of said weathering strip 96, in weathering relation therewith. Each such plate 103, of the sash 6, is bent intermediate of its width to form a flange 108 to support an edge of the glass 28 which is embedded therein in cement 29, as above described.

Said grooves 88 and 89 in the jambs 2 and 3 are similarly adapted to receive, in weathering relation, the flanges 109 and 110 on the opposite side styles of the lower sash 7. Each such member is conveniently formed of a single piece of sheet metal 111. Said flange 110 is reinforced at its edge by bending said sheet metal back upon itself, as indicated at 112. I also prefer to provide each such reinforced portion of said sash flanges with a spring weathering cap 113, preferably formed of sheet bronze, and as indicated in Fig. III. Said flange 109 is J-shaped at its edge to embrace in its bight the flange 99 of said weathering strip 96, in weathering relation therewith. Each such plate 111 of the sash 7 is bent intermediate of its width to form a flange 115 to support an edge of the glass 48 which is embedded therein in cement 49, as above described.

Each of the opposite weathering flanges 102 of the upper sash 6 carries, concealed within the respective grooves 87, respective hook plates 117 adapted for detachable engagement with the ends of respective chains 118 which extend over pulleys 119 which are journaled on shafts 120 in pulley housings formed of two angularly bent plates 121 and 122 which are secured upon the outer face of the respective jamb member 77, in the position indicated by dotted lines in Fig. III. The opposite ends of said chains 118 are respectively connected with counterbalance weights 8 which are suspended for vertical reciprocation within the respective jamb members 76.

Each of the opposite weathering flanges 109 of the lower sash 7 carries, concealed within the respective grooves 88, respective hook plates 125 adapted for detachable engagement with the ends of respective chains 126 which extend over pulleys 128 which are journaled on shafts 129 in said pulley hous-

ing, in the position indicated by dotted lines in Fig. III. The opposite ends of said chains 126 are respectively connected with counter-balance weights 9 which are suspended for 5 vertical reciprocation within the respective jamb members 76. In order to prevent swaying of said weights 8 and 9 into frictional contact with each other, I prefer to interpose the partition web 132 between them, 10 which web is formed of a sheet of metal having its outer edge slit transversely to form oppositely bent flanges 133 by which it is rigidly connected with the inner face of said jamb member 76, conveniently by spot welding 15 the same.

Although single panels of glass 28 and 48 may be mounted in said sashes 6 and 7, as above described; I prefer to divide the area and reinforce large sashes with muntin bars 20 135, as indicated in Figs. I and VI. Said bars are conveniently formed of rolled steel with T-shaped flanges 136, and of less width and consequently less conspicuous than ordinary muntin bars. As indicated in Fig. VI, 25 said bars hold cement 137, such as indicated at 29 and 49, and in which the edges of the glass panels 138 and 139 are embedded.

I prefer to provide each of the sash styles aforesaid with respective hook plates such 30 as indicated at 125 in Fig. VII, and including two hooks connected by a bar fitted within the bight of the respective J flange 109, or 102; said hooks projecting through slots 141 in such flange and said bar being spot 35 welded to the flange, as indicated at 142. Said hooks are so spaced as to fit within respective links in the chain 126 or 118, as indicated. Said hooks are so proportioned that the chains may be readily manually connected 40 and disconnected with respect thereto when the local section of the weathering strip 96 is removed from the jamb.

As shown in Fig. III, the double or so-called "Dutch" edges of the sash weathering 45 flanges 101 and 110 are bent so as to extend in symmetrical relation with the other, single thick, portions of those flanges and thus minimize the area of the flange which may come into contact with the opposed weathering 50 surfaces of the groove in the jamb, with the advantage that the frictional resistance to the vertical movement of the sashes is reduced to the minimum, and that advantage is enhanced by covering those flange 55 edges with the films of bronze 106 and 113 which afford antifriction surface for sliding contact with the opposite walls of the grooves in the jamb in which said sash weathering flanges slide.

60 An important advantage of the form of sash styles above described is that it permits glazing with putty, as distinguished from glazing with strips of metal secured by screws, which is the usual practice. In order 65 to glaze with putty, it is necessary to have a

considerable surface of the style extending transversely to the glass for engagement with the putty. Altho such a surface might be afforded by making the styles L-shaped (leaving off the sash flanges 101 and 110), such construction would leave a space between the outer surface of the style and the inner surface of the jamb, (where the marks 103 and 111 appear in Fig. III,) which would not only be unsightly but would admit the 70 weather, between the upper sash and the jamb. Therefore, it is not only advantageous to provide the sashes 6 and 7 with the extra flanges 101 and 110 to cover the crevices which otherwise would be left between the styles 75 and the jamb but to afford a double weathering joint for each sash. Therefore, I desire to broadly claim a window sash with such double weathering flanges, and particularly such a sash with means upon one of its 80 weathering flanges to engage a sash counter-balance.

However, I do not desire to limit myself to the precise details of construction and arrangement herein set forth, as it is obvious 85 that various modifications may be made therein without departing from the essential features of my invention, as defined in the appended claims.

I claim:

1. In a window structure; the combination with a jamb frame formed of sheet metal and including a weathering groove with opposite faces extending parallel with the direction of movement of the sash; of a sash having a weathering flange fitted in said groove in weathering relation therewith; said flange having its edge in said groove bent back on itself to reinforce it; the bent portion of said flange being bent into symmetrical relation with the main portion of said flange so as to minimize the area of said flange which may come into sliding contact with the side walls of said groove; wherein the reinforced portion of the sash weathering flange is covered with a film of antifriction metal.

2. In a window frame; the combination with a jamb frame member formed of sheet metal and having a groove therein adapted to inclose the flexible connector between a sash and its counterbalance weight; of a sash mounted to slide in said jamb frame and having a weathering flange extending into said groove; and a weathering strip detachably connected with said jamb frame and adapted to conceal said connector and seal the connection between said jamb frame and sash and normally prevent access to said groove; whereby removal of said weathering strip affords access to said connector; wherein the removable weathering strip has a weathering cap formed of sheet spring metal at its edge.

3. In a window frame; the combination with a jamb frame member formed of sheet

metal and having a groove therein adapted to inclose the flexible connector between a sash and its counterbalance weight; of a sash mounted to slide in said jamb frame and having a weathering flange extending into said groove; and a weathering strip detachably connected with said jamb frame and adapted to conceal said connector and seal the connection between said jamb frame and sash and normally prevent access to said groove; whereby removal of said weathering strip affords access to said connector; adapted for double hung sashes, and wherein a single removable weathering strip is common to both sashes.

4. In a window frame; the combination with an inner jamb frame member formed of sheet metal and having two grooves therein adapted to inclose the respective flexible connectors between double hung sashes and counterbalance weights; of a single weathering strip detachably connected with said jamb member, and common to both sashes, and adapted to conceal said connectors and weathering seal joints between said jamb frame member and both sashes.

5. A structure as in claim 4; wherein both sashes have weathering flanges at their edges which are nearest each other; and a single removable weathering strip cooperates with said flanges on both sashes and is detachably connected with the jamb between the respective planes of said sashes.

6. A structure as in claim 4; wherein both sashes have weathering flanges at their edges which are nearest each other, and which are J-shaped with their short limbs nearest each other; and a single removable weathering strip cooperates with said flanges on both sashes, by having its opposite edges bent to extend into the respective J-bights of said sash flanges, and is detachably connected with the jamb between the respective planes of said sashes.

7. A structure as in claim 4; wherein both sashes have weathering flanges at their edges which are nearest each other, and which are J-shaped with their short limbs nearest each other; a single removable weathering strip cooperates with said flanges on both sashes, by having its opposite edges bent to extend into the respective J-bights of said sash flanges, and is detachably connected with the jamb between the respective planes of said sashes; and said weathering strip has respective weathering caps formed of sheet spring metal at each of its edges engaged in said bights.

8. In a window structure, the combination with an inner jamb frame member formed of sheet metal and having grooves therein adapted to inclose the respective flexible connectors between double hung sashes and counterbalance weights; of double hung sashes mounted to slide in said jamb frame

member and having respective weathering flanges at their edges which are nearest each other; said sash weathering flanges extending in respective grooves in said jamb member and having respective hook means within said jamb member for engaging said connectors; and a single removable weathering strip adapted to cooperate with both said sash weathering flanges and detachably connected with the jamb between the respective planes of said sashes.

9. In a window structure; the combination with a jamb frame formed of sheet metal and including a weathering groove with opposite faces extending parallel with the direction of movement of the sash; of a sash having a weathering flange fitted in said groove in weathering relation therewith; said flange having its edge in said groove bent back on itself to reinforce it; the bent portion of said flange being bent into symmetrical relation with the main portion of said flange so as to minimize the area of said flange which may come into sliding contact with the side walls of said groove; wherein the reinforced portion of the sash weathering flange has a weathering cap formed of sheet spring anti-friction metal.

10. In a window structure; the combination with a jamb frame formed of sheet metal and including a weathering groove with opposite faces extending parallel with the direction of movement of the sash; of a sash having a weathering flange fitted in said groove in weathering relation therewith; said flange having its edge in said groove bent back on itself to reinforce it; the bent portion of said flange being bent into symmetrical relation with the main portion of said flange so as to minimize the area of said flange which may come into sliding contact with the side walls of said groove; wherein the reinforced portion of the sash weathering flange carries a resilient weathering cap which is movable on said flange to afford frictional engagement with the jamb frame upon opposite sides of said flange.

11. In a window structure; the combination with a jamb having two parallel vertically extending grooves in the inner face thereof; of a sash having two vertically extending weathering flanges, respectively extending in said jamb grooves; said flanges being spaced with an extensive surface between them extending transversely to the plane of the sash, whereby said sash is adapted for putty glazing; and means on one of said sash weathering flanges within its respective jamb groove, adapted for connection with sash counterbalancing means.

12. A sash structure as in claim 11; wherein in the sash weathering flange provided with the means for engaging a counterbalance is J-shaped and adapted to receive in its bight a weathering jamb member.

13. A window structure as in claim 8; wherein each of the sashes has a weathering flange extending in a groove in the jamb independently of said weathering strip; whereby each sash has weathering connections with the jamb at both its inner and outer faces.
14. In a window structure, the combination with an inner jamb frame member formed of sheet metal and having grooves therein and adapted to inclose the respective flexible connectors between double-hung sashes and counterbalance weights; of double hung sashes mounted to slide in said jamb frame member; each of said sashes having two vertically extending weathering flanges, respectively extending in said jamb grooves; said flanges being spaced with an extensive surface between them extending transversely to the plane of the sash, whereby said sash is adapted for putty glazing; said flanges which are nearest each other having respective means within said jamb member for engaging said connectors; and a single removable weathering strip detachably connected with the jamb between the respective planes of said sashes, adapted to cooperate with both said connector engaging sash weathering flanges.

In testimony whereof, I have hereunto signed my name at Philadelphia, Pennsylvania, this eighteenth day of December, 1929.

ALBERT LINDSAY DOERING.
